UNITED STATES PATENT OFFICE

118,816

DESIGN FOR AN ACROBAT'S HEADSTAND APPARATUS

Costica Floresque, Chicago, Ill.

Application October 25, 1939, Serial No. 87,852

Term of patent 14 years

To all whom it may concern:

Be it known that I, Costica Floresque, a subject of the King of Rumania, residing at Chicago, in the county of Cook and State of Illinois, have invented a new, original, and ornamental Design for an Acrobat's Headstand Apparatus, of which the following is a specification, reference being had to the accompanying drawing, forming part thereof, in which:

I claim:

The ornamental design for an acrobat's headstand apparatus, as shown.

COSTICA FLORESQUE.
